UNITED STATES PATENT OFFICE.

EMMETT E. DAUGHERTY, OF SALINE, MISSOURI.

FENCE-POST.

1,362,772.

Specification of Letters Patent.

Patented May 6, 1919.

Application filed August 28, 1917. Serial No. 188,619.

To all whom it may concern:

Be it known that I, EMMETT E. DAUGHERTY, a citizen of the United States, residing at Saline, in the county of Mercer and State of Missouri, have invented certain new and useful Improvements in Fence-Posts, of which the following is a specification.

My invention relates to fence posts and particularly to metal fence posts wherein 10 the use of staples is eliminated.

An object of my invention is to provide a device of the above mentioned character including means whereby the post may be taken up and moved in less time and with 15 less trouble than has been previously experienced.

Another object of my invention is to provide a device of the above mentioned character which is so formed as to enable one to 20 remove all of the cross-wires of the fence at the same time.

A further object of my invention is to provide a device of the above mentioned character including means whereby the post is 25 reinforced at its base and held in a more stable position.

A still further object is to provide a device of the above mentioned character which is strong, durable, efficient in practice and 30 may be manufactured at a minimum cost.

Other objects and advantages will be apparent during the course of the following description.

In the accompanying drawings forming 35 a part of the description and wherein like numerals are employed to designate like parts throughout the same.

Figure 1 is a front elevation of the device, showing the cross wires of a fence secured 40 thereto.

Fig. 2 is a side view of the same.

Fig. 3 is a sectional view taken on the line 3—3 of Fig. 1, and

Fig. 4 is a sectional view taken on the line 45 4—4 of Fig. 1.

In the drawings wherein for the purpose of illustration is shown a preferred embodiment of my invention, the numeral 5 designates my fence post, which is formed of a 50 sheet of metal and which is provided with a plurality of longitudinally extending

spaced slots 6 in the center thereof. The lower longitudinal edges 7 of the post are cut away diagonally inward as more clearly shown in Fig. 1. This metal is folded at 55 its center and longitudinally to form eyes 8, and the longitudinal edges 9 of the metal are then bent at equal distances from this edge, at right angles to the eyes, and in opposite directions to each other. The portion below the lowermost slot, which forms the eyes in the upper part, is pressed inwardly upon itself so that the outer end of the folded portion is arranged inside the inner end of said folded part to form the 60 65 reinforced rib 10, as is more clearly shown in Fig. 4.

The cross wires are inserted in the slots 6, after which the rod 11 is passed down through the openings in the eyes, and is then 70 bent at its ends as shown by the numeral 12.

It is to be understood that the form of my invention herewith shown and described is to be taken as a preferred example of the same, and that various changes in size, shape, and arrangement of parts may be resorted to without departing from the spirit of the invention or the scope of the subjoined claims.

Having described my invention I claim:— 80

1. A fence post consisting of a single sheet of metal, folded longitudinally, and having the free longitudinal edges of said metal bent in opposite directions and at right angles to said folded portion, said 85 folded portion being pressed inwardly upon itself so that the outer end of said folded portion is arranged inside the inner end of said folded portion to reinforce the post.

2. A fence post consisting of an elongated single sheet of metal folded longitudinally upon itself, the lower folded portion being again folded upon itself to reinforce 90 the post.

3. A fence post consisting of a single 95 elongated sheet of metal having a series of spaced slots intermediate its longitudinal sides and extending longitudinally of the sheet from a point approximately half the sheet to the upper end thereof, said sheet 100 being folded longitudinally intermediate its sides and having its longitudinal edges or

sides bent in opposite directions, and said folded portion below the lowermost slot being bent inwardly upon itself so that the outer end of said folded portion is arranged 5 inside the inner end of the folded portion to reinforce the post.

In testimony whereof I affix my signature in presence of two witnesses.

EMMETT E. DAUGHERTY.
